United States Patent Office

Des. 199,538
Patented Nov. 10, 1964

199,538

CHARM

Tom H. Sand, New York, N.Y., assignor to
Photogen Co., New York, N.Y.

Filed Nov. 30, 1962, Ser. No. 72,658

Term of patent 14 years

(Cl. D45—17)

FIG. 1.

FIG. 2.

FIG. 4.

FIG. 3.

FIG. 5.

FIG. 6.

FIG. 7.

FIG. 8.

FIG. 10.

FIG. 9.

FIG. 11.

FIG. 12.

FIG. 1 is a front elevational view of a charm showing my new design;

FIG. 2 is a rear elevational view of said charm;

FIG. 3 is a top edge view thereof;

FIG. 4 is a side elevational view looking from the left in FIG. 1;

FIG. 5 is a side elevational view looking from the right in FIG. 1;

FIG. 6 is a sectional view taken along the line 6—6 in FIG. 1;

FIG. 7 is a front elevational view of the charm wherein the back plate has a hexagonal configuration and the prongs thereon are increased in size and are lesser in number;

FIG. 8 is a rear elevational view of the charm shown in FIG. 7;

FIG. 9 is a top edge view of the charm shown in FIG. 7;

FIG. 10 is a side elevational view looking from the left in FIG. 7;

FIG. 11 is a side elevational view looking from the right in FIG. 7; and

FIG. 12 is a bottom edge view of the charm shown in FIG. 7.

The broken line showing of the portrait in FIGS. 1 and 7 is for illustrative purposes only.

I claim:

The ornamental design for a charm, as shown and described.
